United States Patent Office.

ABRAHAM JONES, OF CLINTON, ILLINOIS.

Letters Patent No. 96,238, dated October 26, 1869.

IMPROVEMENT IN HAND-LOOMS.

The Schedule referred to in these Letters Patent and making part of the same.

To all whom it may concern:

Be it known that I, ABRAHAM JONES, of Clinton, in the county of De Witt, and in the State of Illinois, have invented certain new and useful Improvements in Looms; and do hereby declare that the following is a full, clear, and exact description thereof, reference being had to the accompanying drawings, and to the letters of reference marked thereon.

The nature of my invention consists in the arrangement of certain devices for operating the treadle-shaft, and the device by which the treadle-shaft is prevented from turning backward.

In order to enable others skilled in the art to which my invention appertains, to make and use the same, I will now proceed to describe its construction and operation, referring to the annexed drawings, which form a part of this specification, and in which—

Figure 1 is a transverse vertical section,

Figure 2, a front elevation, and

Figure 3, a plan view of my machine.

Figure 4 is a longitudinal vertical section of the shuttle-box;

Figure 5 is a plan view of the shuttle-binder; and

Figure 6 is a side view of the gearing which operates the treadle-shaft.

A represents the frame-work of my loom, at the front end of which, near the top, on the inner side, is pivoted a lever, B, one end of which forms the handle to operate the loom, and the other end, being bent downward, is, by means of a bar, C, connected with an arm, D, from the main shaft E, at the rear end of the machine.

On the shaft E, is placed a pulley, F, which, by a cross-belt, is connected with and communicates motion to a pulley, G, placed loosely on the treadle-shaft I.

At the side of the pulley G, on the shaft I, is placed a small wheel, a, having four cogs, at equal distance apart, and on or in the side of said pulley is a spring-pawl, b, which operates in these cogs.

It will then be seen, that if the bent lever B is operated in the same manner as a pump-handle, at the upward stroke of the lever the pawl b will catch on one of the cogs of the wheel a, and turn the treadle-shaft one-fourth around; while, at the downward stroke, the pulley G will move independently of the shaft, so that the pawl will be ready at the next upward stroke to catch the next cog, and turn the shaft another one-fourth revolution.

To prevent the treadle-shaft I from turning backward when the pulley G does, I provide said shaft, at one end, with a small ratchet-wheel, c, in which a pawl, d, works, so as to hold the treadle-shaft when turned forward.

On the shaft I are placed the tappets H H, which

work the treadles J J when the shaft is turning, the treadles operating the harness in the usual way.

To the ends of the main shaft E, fly-wheels K K are secured, which wheels are, by means of rods L L, connected with the batten, these rods being, on a full-sized machine, pivoted to the fly-wheels, about eight inches from the centre. It will be seen that the batten will move four times backward and forward for each revolution of the treadle-shaft.

M is the top piece of the batten, or hand-piece for working the batten back and forth, and receives the upper part of the reed N, the lower side of which is held by the bar O.

The bar O has a shuttle-box, P, at each end, and the shuttle passes over said bar, from one box to the other.

When the shuttle enters the box P, it strikes a picker, Q, placed in the same, which picker, as it moves to the outer end of the box, operates the shuttle-binder R, pivoted in a slot on the front side of the box, so that the shuttle will be held temporarily in the box, but not so hard as to prevent it from moving inward again when force is applied to the picker.

The outer end of the shuttle-binder R is bevelled, as shown in fig. 5, so as to allow the picker to move in freely, and cause the inner end of the shuttle-binder to hold the shuttle.

The picker is connected by a strap, e, which passes through an oblique slot in the bottom of the shuttle-box, with the picker-staff S, the lower end of which is pivoted to a cross-bar, connecting the lay-swords.

The upper end of the picker-staff works in a slot in the bar T, under the batten, above mentioned.

When the picker is moved outward by the shuttle, the upper end of the picker-staff is, at the same time, by means that will be hereinafter set forth, moved outward, and is caught by a trigger, V, on the under side of the bar T.

The picker-staves S S are connected by a spring, X, as seen in fig. 2, so that when the trigger V, which holds its picker-staff, is operated, upon releasing said staff this spring forces the upper end of the staff inward, thereby causing the picker to throw the shuttle through the shed. At the same time, the other staff, S, is drawn outward, to be, in like manner, caught by its trigger and released again.

The picker-staff is moved outward by a strap, f, which passes around a pulley at the end of the batten, and is attached to a connecting-rod, Y, which is pivoted to the outer side of the fly-wheel K, in a full-sized machine, about four inches from the centre, the two connecting-rods being so placed as to allow the alternate motion of the picker-staves.

The trigger V is operated by a lever, Z, pivoted on the side of the frame A, so as to release the picker-

staves at the proper moment. This lever is operated by an eccentric, *g*, on the end of the treadle-shaft *I*.

A' A' are the uprights of the batten, working on rockers *B' B'*, which are prevented from sliding by a pin inserted in a slot on the bottom bars of the frame.

The yarn-beam *C'* has a pulley, *D'*, around which is placed a rope or chain, attached to a lever, *E'*, which is pivoted to the inner side of the frame, by which means the letting off of the warp may be regulated while weaving.

The cloth-beam *F* is, at one end, provided with a ratchet-wheel, *h*, and on the journal of said cloth-beam is a crooked or bent lever, *l*, provided with a pawl, *m*, which catches in the ratchet-wheel on the take-up roller. The end of the lever *l* rests on and is worked by the batten.

A spiral spring, *n*, attached to the under side of the lever *l*, forces the lever downward again, winding the cloth up on the beam.

To this spring *n* is attached a cord, *p*, which passes around the pulley *o*, in the lower bar of the frame *A*, then upward to a pin, *r*, by which means the spring

can be tightened or loosened at pleasure, thus regulating the rapidity with which the cloth is taken up.

To prevent the cloth from unwinding from the cloth-beam, a detent, *i*, is provided, which works in the ratchet-wheel *h*, for that purpose, as seen in fig. 1.

I have described many parts that are old; but

What I claim as new, and of my invention, and desire to secure by Letters Patent, is—

1. The lever *B*, connecting-bar *C*, arm *D*, main shaft *E*, and fly-wheels *K K*, all constructed as described, and arranged to operate the lay, substantially in the manner herein set forth.

2. The main shaft *E* and pulley *F*, connected by a cross-belt to the ratchet-pulley *G* on the treadle-shaft *I*, constructed and arranged as shown, to operate the treadle-shaft.

In testimony that I claim the foregoing, I have hereunto set my hand, this 8th day of March, 1869.

ABRAHAM JONES.
